DESIGN FOR A BUTTON BACK

Jack Schneck, New York, N. Y., assignor to National Button Works, New York, N. Y., a partnership composed of Jack Schneck and Paul Herber

Application October 2, 1940, Serial No. 95,555

Term of patent 3½ years

To all whom it may concern:

Be it known that I, Jack Schneck, a citizen of Austria, residing in the city, county, and State of New York, have invented a new, original, and ornamental Design for a Button Back, of which the following is a specification, reference being had to the accompanying drawing, forming part thereof, wherein:

Fig. 1 is a side elevation of a button back showing my new design; and

Fig. 2 is a top plan view of Fig. 1.

I claim:

The ornamental design for a button back, as shown.

JACK SCHNECK.
